CLAIM

The ornamental design for an electronic device, as shown and described.

DESCRIPTION

FIG. 1 is a top, front, and left-side perspective view of an electronic device showing our new design;

FIG. 2 is a bottom, rear, and right-side perspective view of the electronic device of FIG. 1;

FIG. 3 is a front elevational view of the electronic device of FIG. 1;

FIG. 4 is a rear elevational view of the electronic device of FIG. 1;

FIG. 5 is a right-side elevational view of the electronic device of FIG. 1;

FIG. 6 is a left-side elevational view of the electronic device of FIG. 1;

FIG. 7 is a top plan view of the electronic device of FIG. 1; and,

FIG. 8 is a bottom plan view of the electronic device of FIG. 1.

The outermost broken tines immediately adjacent to the full line showing of the claimed design represent the bounds of the claimed design while all other broken tines are directed to environment and are for illustrative purposes only; the broken lines form no part of the claimed design.
